WRIST WATCH STRAP

Abraham Schwalberg, Brooklyn, N. Y.

Application August 14, 1931, Serial No. 557,035

14 Claims. (Cl. 224—4)

This invention relates to wrist watch straps and particularly, to that type in which the strap body is made largely of flexible material such as leather, fabric or the like, and to the means for removably maintaining the strap in place upon the wrist of the wearer.

My invention contemplates the provision of a flexible strap body, so constructed as to present integral, smooth and finished edges throughout the strap, which are firmly held against possibility of separation, in which body rough edges necessitating the use of paint or the like, are eliminated, in which a minimum amount of contrasting thicknesses of material are provided, thereby avoiding abrasive action against the wrist of the wearer, in which a variety of ornamental and decorative effects may be produced, and in which comparatively thin, high grade leathers, or fabrics, such as kid, silk or the like may be used.

My invention further contemplates the provision of simple and efficient means of the snap fastener type, for securing the ends of the strap body separably in proper position about the wrist of the wearer.

The various objects of my invention will be clear from the description which follows, and from the drawing, in which,

Fig. 1 is a perspective view of my invention as it appears secured to a wrist watch and opened up or unfolded ready for removal from the wrist.

Fig. 2 is a vertical section and partial perspective view of a portion of a strap body, showing the stitching therefor and showing a metallic loop which may be used in connection therewith, if desired.

Fig. 3 is a similar view of a modified form of one of the strap body elements wherein suitable reinforcing material is used.

Fig. 4 is a similar view of another modified form of my new strap body element wherein a separate piece of material is used for a facing.

Fig. 5 is a similar view of the same but showing a modified form wherein reinforcing material is inserted in the interior in the strap.

Fig. 6 is a similar view of another modified form of the strap body element.

Fig. 7 is a similar view of a modified form of the strap body wherein a sufficiently wide member takes the place of the pair of narrow members illustrated in Fig. 2.

Fig. 8 is a top plan view of one form of the fastening means arranged at one of the ends of the strap, and designed to be used in connection with the attaching pin of a wrist watch.

Fig. 9 is a rear elevation of the same as it appears attached to the strap body.

Fig. 10 is a view similar to Fig. 8, of a similar connection which is, however, removable from the strap body instead of being permanently attached thereto.

Fig. 11 is a rear elevation of the same.

Fig. 12 is a front elevation of part of a fastener carrying element showing the socket therein.

Fig. 13 is a vertical section of the snap fastener 10 means for removably securing the parts of the strap together.

Figs. 14 and 15 are similar views of modified forms of the same, and

Fig. 16 is a front elevation of a modified form 15 of the fastening means for the separable ends of the strap parts.

In that practical embodiment of my invention which I have illustrated by way of example, my improved wrist watch strap includes a pair of 20 similar strap body members, each designated generally by the numeral 10, said strap body carrying at one of its ends, suitable fastener elements 11, designed to connect said end of the strap body to the pin 12 of a wrist watch 13. My improved 25 strap terminates at the other or separable end in a suitable hinge buckle 14, or other means intended to permit the separation of the ends 15 and 16 of the strap body so that the strap may be put on and taken off the wrist of the wearer 30 with ease and rapidity.

Since the strap body 10 forms one of the features of my invention, said body will now be described in detail.

As indicated in Figs. 1, 2, 9, 11 and 16, each 35 of the sections 10 of the strap body preferably consists of two similar and preferably, though not necessarily, edge-abutting flexible bands, each made of suitable comparatively thin, but flexible, non-resilient and non-metallic material 40 such as leather, silk or other suitable material capable of receiving various types of ornamentation, which ornamentation may be of the surface or of the embossed type, or may consist of suitable coloring. By making the strap body bands 45 in the manner soon to be described, it becomes possible to use thin materials and particularly, high grade thin leathers such as kid or the like, and to produce various decorative effects by the use of differently ornamented or colored material 50 in the different bands, and/or in the different parts of each band.

Referring particularly to Fig. 2, I have there shown one band as 20 of the strap body 10, arranged in edge-abutting relation to a similar 55

band 21, though it will be understood that the bands 20 and 21 may be somewhat spaced apart to separate the adjacent edges 22 and 23 thereof, and to avoid frictional wear therebetween, as may be found convenient or desirable. The bands 20 and 21 being similar to each other, a description of one will suffice for both. Still referring to Fig. 2, the band 20, for example, consists of a comparatively wide piece of comparatively thin material having the edge portions thereof folded inwardly or rearwardly so that one edge flap 24 is arranged in the interior of the band, and the other edge flap 25 is arranged behind the flap 24 to form the inner or rear face 15 of the band, and so that only one exposed terminal edge 26 of the flap 25 remains unfinished. It will be seen that by thus folding the strip constituting the band 20, not only is the edge 22 rounded and thereby finished by an integral 20 rounded fold edge to present a good appearance, but that the strength and wearing properties of the band are increased, and the necessity is avoided of resorting to the various expedients heretofore used for rendering inconspicuous the 25 raw unfinished edges normally presented in leather or similar wrist watch straps, such as painting, beading, or calendering the edges. The unfinished edge 26 furthermore is comparatively thin, and is arranged on the back or inner face 30 of the band and in the operative position of the strap, is therefore invisible.

The flaps 24 and 25 are secured together and at the same time secured to the front section 27 of the band, by means of a line of stitching 28 passing through the three thicknesses of material thus provided adjacent the upper edge 29 of the band. A similar line of stitching 28 is arranged adjacent the rounded finished edge 22 at the lower edge of the band, and serves to secure the 40 unfinished edge 26 and the folds in place. It will be understood that said unfinished edge 26 terminates slightly above the finished edge 22, and being arranged on the inner face of the band, is concealed by the wrist when the strap is in use. 45 Similarly, in the band 21, the corresponding unfinished edge 30 is arranged at the upper edge of the band just below the finished edge 23. One or more metallic loops as 31, bent of suitable wire or cut from tubing, may, if desired, be 50 arranged on the strap to aid in maintaining the bands 20 and 21 in their proper relation and for purposes of ornamentation.

Said loops 31 may be suitably ornamented, as by surface or embossed or engraved ornamentation, or said loops may be omitted, if desired.

It will be understood that the stitching 28 and 48 may also be omitted should it be found advisable to do so, and that suitable adhesive material may be substituted therefor, though it will 60 be further understood that both adhesive and stitching may be used to hold the parts of the strap together. It will further be seen that in the bands 20 and 21, at least three thicknesses of material are provided, thereby producing a 65 durable, though flexible band of uniform thickness and width throughout, except for the comparatively insignificant spacing of the edges 26 and 30 from the respective edges 22 and 23.

In that form of my improved strap body illustrated in Fig. 3, which is similar to the form just described, the interior flap 24 is spaced from the front section 27 by the layer 32 of reinforcing material arranged therebetween. Said reinforcing material consists preferably of suitable material, such as buckram, leather or the like,

which is stiff as compared to the soft leather or fabric used for the exposed or visible portions of the band. The stitching 28 and 48 in this form of my invention passes through the reinforcing layer and serves to maintain the various flaps 5 and sections in their proper positions, or adhesive may be used as above explained, four thicknesses of material being provided to assure the proper body or thickness which is desirable in some cases.

In that form of my new strap body shown in Fig. 4, the band 33 consists preferably, of a rear section 34 and a pair of similar front flaps 35 and 36, the adjacent edges of which may meet each other at the rear part of the band, or may be 15 spaced slightly apart. Said edges, however, are concealed and reinforced by the front facing 37 of comparatively thin material secured to the remainder of the band by adhesive, and/or by the lines of stitching 38 and 39 which pass through 20 the band.

It will be understood that the facing strip 37 may be of a color contrasting with that of the rear section 34, or may carry contrasting surface or embossed ornamentation so as to present an 25 ornamental appearance suitably harmonizing with that of the remainder of the band. It will further be noted that the facing strip 37 extends substantially across the entire width of the band 33 so as to provide three thicknesses of material throughout the entire band.

Referring now to that embodiment of the band shown in Fig. 5, a layer of reinforcing material 40 is arranged between the rear section 34 and the forwardly disposed fold sections or flaps 35 and 36, so as to stiffen the band and make it more durable and of less flexibility than the form shown in Fig. 4, thereby providing four thicknesses of material substantially throughout the entire band, one of said thicknesses being the 40 stiffening layer 40.

In that form of my new band shown in Fig. 6, a stiffening layer 40 is provided not only in the main section 41 of the band, but a similar reinforcing layer 42 is provided in the auxiliary or front facing section 43. In order that the edges of the flaps 44 and 45 of the main section are not aligned or do not register with the edges of the flaps 46 and 47 of the auxiliary section 43, the flap 44 is made narrower than the flap 45 and similarly, the flap 46 is made wider than the flap 47. By means of this arrangement, the adjacent edges of the flaps of the main and auxiliary sections are maintained out of registry with each other whereby any possibility of lumps, 55 ridges or depressions is avoided. Suitable adhesive or lines of stitching as 28 and 48 as hereinbefore described, unite the main and auxiliary sections with the reinforcing layers in their proper positions.

It will be seen that in this form of my new band, different materials may be used for the different sections, and that no rough or unfinished edges are anywhere presented, the folds or bands forming the peripheral edges of the sections being 65 suitably rounded and integral. It will further be understood that the possibility of using material of contrasting appearance and of variable designs is enlarged, so that the scope and variety of the ornamental effects which can be obtained 70 are considerably widened.

While it will be understood that the bands I have described hereinbefore are preferably intended to be used in pairs arranged edge to edge, it will also be understood that if desired, a single 75

band may be made of sufficient width to extend across the entire width of the strap, as illustrated by the band 50 of Fig. 7. In said figure, I have shown a band similar in construction to the band 20 but of double the width so that a single band only is used across the width of the strap to form the body thereof. The construction of the band 50 may be that shown in any of the Figs. 2 to 6 inclusive, as has been hereinbefore described, 10 though only the folded structure of Fig. 2 has been illustrated.

It will be understood that means are employed for securing an end of each of the strap body sections 10 to the pin 12 of the wrist watch 13. 15 As illustrated in Figs. 8 and 9, the securing means 51 may take the form of a sheet metal member or members permanently secured to the end 52 of the strap body. Spring loops or hooks as 53 are provided at the end of the securing member 51, 20 into the opening 54 of which, the pin 12 of the watch may be inserted, or about which pin the hooks may be passed. A suitable sheet metal member as 55 of L-shaped section may be arranged transversely across the bands 20 and 21 to provide a bearing surface for the ears 56, which are bent over on to the member 55 to hold the members 51 and 55 to the bands.

In the form shown in Figs. 10 and 11, the movable member 60 is substituted for the member 55, 30 and is suitably pivoted to the ears 61 as at 62, and terminates in suitable teeth 63 designed to engage the inner faces of the bands 20 and 21 and thereby aids in removably securing the hooks or loops 53 to the bands. It will be understood that by 35 reason of the removable attachment of the hooks 53 to the bands, the effective length of the strap body sections 10 may be somewhat varied, as may be desired, by moving said hooks along the strap body before rotating the member 60 into 40 locking position.

At the other ends of the strap body sections 10, suitable means are provided for removably securing said ends together, to close the strap about and in proper engagement with the wrist, and 45 to make the strap of the proper diameter. As illustrated in Fig. 1, the separable fastening means takes the form of a hinge buckle 14, comprising a buckle section 70 and a pair of openable hinged sheet metal fastener-elements supporting 50 sections 71 and 72, said sections being of the general type well known and customarily used in the art for this purpose.

The socket-carrying section 71 is suitably pivoted at one of its ends to the buckle section 70 55 as by means of the pin 73. The other end of the section 71 is hinged, as by means of the hinge 74, to the stud-carrying section 72. Said section 72 is suitably secured to the body section 10 as by means of a connecting element 75, similar either 60 to the fastener 51 or to the fastener 61, but wherein the hooks 54 are omitted and the section 72 substituted. In other words, said section 72 may be removably or permanently attached to the body 10. Where it is removably secured to the body as by means of a member 60, it will be understood that adjustment of the effective length of the body 10 may be obtained by releasing the member 60 and then moving the buckle 14 over the body in the proper direction to lengthen or 70 shorten the operative length thereof. Similarly, the buckle section 70 may be secured to the other strap body section 10 by similar permanent or adjustable or removable means.

The section 72 is further provided with a suitable snap fastener stud 76, while the section 71

is provided with a suitable cooperating snap fastener socket 77. It will be understood that the sections 71 and 72 are overlapped by rotation about the hinge 74 into the proper position to carry the stud 76 into registry or axial alignment with the socket 77, and that the stud may then be snapped through the socket to retain the parts in their folded positions and to maintain the strap against opening on the wrist of the wearer.

It will further be understood that the stud 10 may be a resilient stud or a non-resilient stud, and that the socket 77 may similarly be a resilient or a non-resilient socket. However, as is customary in the snap fastener art, if one of the elements is resilient, the other is usually made 15 non-resilient. However, it will be understood that both elements may be made resilient for purposes of ease of attachment and detachment, and as will be more fully explained hereinafter.

The socket element 77 may consist, as is well 20 illustrated in Figs. 1, 12, 13, 15, and 16, of a perforation 78 of slightly less diameter than the greatest diameter of the stud 76. As shown in Fig. 14, the perforation 78 provides a non-resilient socket. Should it be desired, however, to make 25 the socket resilient, as is sometimes advantageous, I prefer to provide a series of slots or slits 79 extending radially outwardly from the circumference of the perforation. (Figs. 1, 12 and 16). Such slits provide resilient fingers 80 therebetween which yield to some extent under the pressure of the stud, and thereby permit the passage of a resilient or non-resilient stud into detachable engagement with the walls of the perforation. The resilient stud 76 is of the "bird cage" type, 30 being provided with a series of spaced slots or slits 81 arranged in radiating vertical planes passing through the axis of the stud, the stud terminating in a suitable flange 82 arranged on one face 83 of the section 72. A flanged eyelet 40 84 is arranged on the other face 85 of the section 72, the hollow eyelet portion 86 thereof passing through an aperture 87 in the section 72 and spread against the interior wall of the stud to hold it in place. Said aperture is preferably of 45 greater diameter than that of the eyelet to permit transverse movement of the stud in all directions to a limited extent. It will be seen that should the stud 76 fail to register accurately with the socket perforation 78, said stud, owing to its 50 curved end, under the axial pressure thereon, may move slightly on the section 72 to obtain perfect registration in order to enter the perforation 78 of the socket without undue pressure.

As shown in Fig. 14, however, the slits 72 are 55 eliminated and the socket is made non-resilient by the use, merely, of the perforation 78, and an eyelet, if desired.

As illustrated in Fig. 15, the stud 93 may be of a non-resilient type either integral and pressed 60 out from the section 72 or suitably attached thereto by means of a suitable eyelet or rivet 91.

As shown in Fig. 16, the buckle 14 may be dispensed with and the cooperating snap fastener elements may be separately secured to the respective ends of the strap bodies 10 without being hinged together. In that case, the snap fastener support 95 is provided with ears 96 which may support a pivoted member 60 of the type shown in Figs. 10 and 11, or which may be bent 70 into firm engagement with the bands 20 and 21 and thereby permanently secured thereto.

The ends of the fingers 80, as shown in Fig. 16, may if desired, be bent upwardly and then outwardly to provide a greater and rounded area for 75

engagement with the stud and to prevent injury to the stud on its repeated passage through the socket.

When a removable connection is used, the support 95 is adjustable on the strap body and when the connection 51 is used, the support 95 or 97 is permanently secured and non-adjustable. The support 95 carries the stud 76 while the similar support 97 is provided with the socket 78 and is similarly secured to the bands 20 and 21 by means of the ears 96 and/or by the pivoted member 60. When this type of annular snap fastener connection is used, it will be understood that the strap may be completely opened and removed from the wrist of the wearer merely by bringing the ends thereof together and snapping the stud through the socket.

In any case, the individual bands 20 and 21 may adjust themselves automatically to the shape of the wearer's wrist in a manner not possible in straps not provided with separate bands.

It will be seen that I have provided a simple wrist watch strap capable of being secured in place on the wrist of the wearer adjustably or non-adjustably by means of a simple, inexpensive but efficient snap fastener device, that the strap presents a highly ornamental appearance with no rough or unfinished edges exposed to view, that the strap may be made of contrasting materials, or of materials of contrasting colors and designs in great variety to produce numerous ornamental effects, that the strap may adjust itself to fit the wrist, and that I have produced a strap well designed to meet the severe requirements of practical use.

While I have shown and described certain specific embodiments of my invention, it will be understood that I do not intend to limit myself thereto but intend to claim my invention as broadly as may be permitted by the state of the prior art and the scope of the appended claims.

I claim:

1. In a wrist watch strap, a flexible body consisting of a pair of similar sections, each of said sections comprising a pair of similar but independent comparatively wide and thin bands arranged in edge-abutting relation and each of said bands including a comparatively thin but wide strip of imperforate flexible material folded transversely upon itself to provide integral rounded edges on said band and to provide at least three thicknesses of material, each of said thicknesses being substantially as wide as the band, at least one of the edges of the strip being arranged in the interior of said band, and the other edge adjacent the edge of the band, and a pair of lines of stitching adjacent to and parallel to said edges and passing through all the thicknesses of material.

2. In a wrist watch strap, a body member comprising a strip of flexible material having its edge portions folded inwardly toward each other to bring said edge portions into the same plane and to provide integral edges on said strip and a front facing member covering the edges of said strip and secured to said strip by stitching passing through the folded portions and thereby providing at least three thicknesses of material in said body member, said body member being thereby reinforced and stiffened, and being of substantially uniform width and uniform thickness.

3. In a wrist watch strap provided with end hooks adapted to engage the ears of a wrist watch and having a pair of body sections adapted to be separably fastened together, each body section

comprising a pair of inwardly folded leather body members similar to each other and each of substantially rectangular cross-sectional outline and each comprising a normally stretchable leather sheet having its edge portions infolded to provide an integral longitudinal edge fold, a plurality of thicknesses of material in each of said body members, and a line of stitching passing through each of the body members and substantially parallel to the edge fold thereof for maintaining the body members in their folded positions, said body members being arranged in the body section with the corresponding edge folds thereof in adjacent relation and movable laterally with respect to each other by the action of the wrist of the wearer to ventilate the wrist.

4. In a wrist watch strap, a flat body band substantially unstretchable under the stresses of normal use, adapted to resist the effect of perspiration, comprising a comparatively wide but thin leather strip, the longitudinal peripheral edge portions of said strip being folded inwardly and transversely upon the remainder of the strip to reduce the original width of the strip and to provide a plurality of thicknesses of material, the outermost thicknesses of material providing flat, unwrinkled surfaces of greater width than the thickness of the strip, integral rounded sides on the band and a line of stitching adjacent to and parallel to each of said edges and passing through all of the thicknesses of material for maintaining the band in its folded form.

5. In a wrist watch strap, a body member resistant to perspiration and substantially unstretchable under the stresses of normal use comprising a pair of similar but independent comparatively wide and thin bands arranged in edge adjacent relation, each of said bands including a comparatively thin but wide imperforate strip of leather the longitudinal edge portions of the strip being folded transversely and inwardly upon the remainder of the strip to form integral edge folds and to provide a plurality of thicknesses of material, stitching passing through all the thicknesses of the band adjacent each of said edges to hold the band in folded position and thereby to increase the resistance of the band to stretching and to perspiration, said band having a wide inner surface, flat throughout its entire width, and means at the ends of the bands for securing the ends of said pair of bands in assembled relation and for securing the assembled bands to other articles whereby ventilation between the adjacent edges of the band is permitted to reduce the effect of perspiration of the wrist thereupon.

6. In a wrist watch strap, a leather body member comprising a wide but thin leather sheet having its edge portions folded transversely and inwardly on itself to provide integral longitudinal edge folds, said edge portions constituting a pair of flaps, each of a single thickness of material, and stitching adjacent each of the edge folds of said member securing the folded parts of said sheet together.

7. In a wrist watch strap, a body member comprising a wide but thin leather strip having its longitudinal edge portions folded inwardly on itself to provide integral longitudinal edge folds, said edge portions constituting a pair of flaps each of a single thickness of material, a thickness of reinforcing material less stretchable than leather enclosed in the folded band and concealed thereby, and stitching parallel to and adjacent each of the edges and securing the reinforcing

thickness and the folded parts of said band together.

8. In a wrist watch strap, a body member comprising a pair of similar co-planar bands, each of said bands comprising a wide but thin and imperforate strip of leather and having its edge portions folded inwardly from the sheet to provide at least three thicknesses of material, and stitching securing said thicknesses of each band together, said bands being independently movable under the action of the wrist of the wearer and being arranged in edge adjacent relation to to permit the passage of air therebetween and thereby to ventilate the wrist of the wearer, and means for securing the adjacent ends of said bands together to maintain the ends of said bands in their co-planar relation while permitting relative lateral and transverse movement of the intermediate portions of the bands, said means being adapted to attach the body member to other articles.

9. In a wrist watch strap, a flexible body consisting of a pair of similar sections, each of said sections comprising a pair of similar but independent comparatively wide and thin bands arranged side by side, and each of said bands including a comparatively thin but wide imperforate leather strip folded transversely upon itself to provide at least three thicknesses of material, each of said thicknesses being substantially as wide as the band at least one of the edges of the strip being arranged in the interior of said band and the other edge adjacent the edge of the band, and a pair of lines of stitching adjacent to and parallel to the edges of the band and passing through all of the thicknesses of material.

10. In a wrist watch strap, a body member comprising a comparatively wide first strip of imperforate flexible material folded transversely upon itself, integral rounded terminal edges on the folded strip, a second facing strip arranged on one of the faces of the folded first strip, a third reinforcing strip of flexible material less stretchable than the material of said first and second strips, said third strip being narrower than said first strip and arranged in contact with one of the faces of said first strip and being concealed by the folded parts of said first strip and resisting the stretching of said body member, and a pair of lines of stitching adjacent to and parallel to said edges and passing through all of said strips and through the folded parts thereof.

11. A flexible body member substantially unstretchable under the stresses of normal use, said member being adapted for use in a wrist watch strap, comprising a thin but wide leather sheet folded upon itself to reduce the sheet to a band of substantially a third of the original width of the sheet and to form at least three thicknesses of material therein, one of the side edges of the sheet being arranged in the interior of the band and the other side edge of the sheet being arranged at the exterior of the band but in spaced relation to the adjacent edge of the band, a pair of lines of stitching passing through the thicknesses of material in said band inwardly of and parallel to each of the respective edges of the band, and securing the band in its folded position, a similar band independent of the first-mentioned band and movable laterally thereto except at its ends under the action of the wrist of the wearer,

and arranged with the terminal edge of the sheet from which it is formed adjacent to the similar edge of the first-mentioned band to permit the passage of air therebetween and to ventilate the wrist of the wearer, and a fastener element securing the adjacent ends of said bands together to hold said bands against separation at their ends, and having means thereon for securing the band to another element.

12. A band for a wrist watch strap comprising a wide and thin leather sheet folded transversely and inwardly to provide a main section and two unfolded overlapping flaps each of a single thickness of material, said flaps providing at least three thicknesses of material in the strap, one terminal edge of the sheet being arranged in the interior of the band, the other terminal edge of the sheet being exposed at the inner face of said band and adapted to be arranged adjacent the wrist of the wearer, a rounded edge at one peripheral edge of the band comprising a fold integral with the outermost thicknesses of the material of the band, and forming a finished edge on the band, a second integral edge fold on the band forming the other edge of the band, a line of stitching spaced slightly inwardly from and parallel to one of the edges of the band, and a similar line of stitching spaced slightly inwardly from the other edge of the band, said lines of stitching securing the various thicknesses of the material of the band permanently together.

13. In a wrist watch strap having a pair of body sections and having means for separably securing the sections together and to the ears of a wrist watch, a pair of transversely folded similar body members comprising each of said sections, each of said members being of substantially rectangular cross-section and independent of the other throughout the length thereof except at its ends, each of said members comprising a thin leather strip infolded at its free edges to increase the resistance of the members to stretching and to perspiration, said members being arranged in edge to edge relation to bend longitudinally on the wrist of the wearer, and being adapted for automatic self-adjustment in a lateral direction to conform to the shape and to ventilate the wrist of the wearer, while distributing the pressure of the strap on an area of the wrist substantially equal to the area of said body section.

14. A band for a watch strap or the like comprising a wide and thin leather sheet folded transversely and inwardly to provide a main section and two unfolded overlapping flaps each of single thickness of material, said flaps providing at least three thicknesses of material in the strap, one terminal edge of the sheet being arranged in the interior of the band, the other terminal edge of the sheet being exposed at one face of said band, a rounded edge at one peripheral edge of the band comprising a fold integral with the outermost thicknesses of the material of the band, and forming a finished edge on the band, a second integral edge fold on the band forming the other edge of the band, a line of stitching spaced slightly inwardly from and parallel to one of the edges of the band, and a similar line of stitching spaced slightly inwardly from the other edge of the band, said lines of stitching securing the various thicknesses of the material of the band permanently together.

ABRAHAM SCHWALBERG.
